US00D530619S

(12) **United States Design Patent** (10) **Patent No.:** **US D530,619 S**
Stockwell et al. (45) **Date of Patent:** **** Oct. 24, 2006**

(54) **BOTTLE PORTION**

(75) Inventors: **Machelle D. Stockwell**, Bradenton, FL (US); **Stuart Leslie**, Larchmont, NY (US); **Charles A. Curtiss**, Norwalk, CT (US); **Tomohito Asano**, New York, NY (US); **David Deemer**, Adrian, MI (US); **Hassan Mourad**, Canton, MI (US)

(73) Assignee: **Stokley-Van Camp, Inc.**, Chicago, IL (US)

(**) Term: **14 Years**

(21) Appl. No.: **29/258,191**

(22) Filed: **Apr. 18, 2006**

Related U.S. Application Data

(60) Continuation of application No. 29/219,531, filed on Dec. 17, 2004, now Pat. No. Des. 519,036, which is a division of application No. 29/188,009, filed on Aug. 11, 2003, now Pat. No. Des. 502,877.

CLAIM

The ornamental design for a bottle portion, as shown and described.

DESCRIPTION

FIG. 1 is a perspective view of a bottle portion showing the new design;

FIG. 2 is an elevational view thereof, the opposite elevational view being identical;

FIG. 3 is another elevational view thereof, representing a half rotation of the bottle portion about its vertical axis from the elevational view depicted in FIG. 2, the opposite elevational view being identical;

FIG. 4 is a top plan view thereof; and,

FIG. 5 is a bottom plan view thereof.

The broken line environmental showing is for illustrative purposes only and does not form a part of the claimed design.
